MACHINE FOR OPERATING UPON SHOE-BOTTOMS

Lester S. Macdonald, Beverly, Mass., assignor to
 United Shoe Machinery Corporation, Paterson,
 N. J., a corporation of New Jersey

Application October 15, 1931, Serial No. 568,988

87 Claims. (Cl. 12—19.2)

This invention relates to machines for operating upon the bottoms of shoes, it being of especial utility in connection with the securing to one another of portions of the heel-ends, as the heel-seats.

The various elements of the heel-seats of shoes are customarily attached to one another by driving through the outsole, counter-flange, upper-material and insole a series of fastenings inserted as close to the edge of the insole as is feasible, this relation producing a tight rand-crease. This operation may be effected expeditiously and with the advantage of being able to shape the surface of the outsole to the approximate form of the end 15 of the heel which is to engage it, if all the seat-securing fastenings are driven simultaneously while the work is under molding pressure. When the fastenings are to consist of some relatively soft material, as pegs of paper or the like, it is 20 not only desirable to prick openings in the seat in preparation for the insertion of the fastenings, but also to carry the openings fully through the seat-material to the last-plate, so no substantial resistance to the driving shall be encountered. 25 It is also important that the length of the fastenings shall correspond with considerable accuracy to the thickness of the material which they are to secure. It is, therefore, an object of my invention to provide for the simultaneous insertion 30 of a plurality of fastenings under uniform and readily controllable conditions throughout the entire gang.

In attaining this object, a feature of the invention is furnished by a plurality of movable tools, which may be awls, combined with a movable operating member and connections therefrom to each tool, said connections being arranged to yield independently of one another, as against the resistance of such a pressure-transmitting medium as a contained fluid common to plural tools, upon the encountering by said tools of a predetermined resistance. Thus, each tool may penetrate the heel-seat of a shoe until it is stopped by the plate of the last within the shoe and without mutilation of said plate, while each of the associated tools acts similarly without interfering with its companion. To enable the work-penetrating force to be varied to meet the particular conditions encountered, means common to all the tools is furnished for varying the yieldability. There may be a source of fluid-pressure, as a pump, connected to all the tools, this source being bypassed through an adjustable valve controlling the effective pressure applied. A co-operating cylinder and piston in the connections to each tool

receive this pressure and are adapted to yield in accordance with the adjustment.

A further feature of the invention involves the locking of yieldable connections for movable tools against such yield. Two tools may be employed 60 in an operating section, for example an awl and a driver, with actuating connections common to both, said connections having portions allowed to yield during the operation of one tool and then the portions of the connections joined unyieldably during the operation of the companion tool. 65 Thus, the heel-seat of a shoe may be pricked yieldably through its entire thickness, and then, by means of the same actuating connections, a fastening may be driven positively into the opening thus formed. This latter effect may be brought about by the locking of a fluid against yield in the actuating connections, or by the direct joining of the parts by a member movable upon one portion of the connections and engaging 70 another, or both locking means may be employed simultaneously. The first-mentioned locking action is shown herein as resulting from the movement of a valve in the connections.

In the common connections for plural tools 80 which may go to make up an operating section there is included, as a feature of the invention, a novel organization having a reciprocatory actuating member associated with a holder in which both an awl and a driver are mounted to reciprocate. There is provided means by which the holder is moved to cause either of the tools to be aligned with the actuating member, which may then produce its effect upon the registering tool. The associated tool is at the same time retained 90 against movement, as by engagement with a guide for the actuating member. For the simultaneous insertion of a plurality of fastenings, there being an awl and a driver involved in the insertion of each fastening, means is preferably 95 provided for simultaneously operating the holder of these tools to align either the awl or the driver with a corresponding passage of a die-block or member through which fastenings are to be inserted. I have also shown means for simultaneously operating all the actuating members of the tools which have been brought into position in different sections. Both operating means appear herein as in the form of plungers acting upon levers which respectively serve to shift the 100 holders and to actuate the tools.

The operating position of each tool is determined by engagement with such a device as the die-block previously mentioned, there being a different block for each fastening-inserting design. 110

Each of these die-blocks has a groove for each tool or tool-section which is to be active, said groove extending through the edge of the block to a tool-locating recess. Still another feature 5 of the invention concerns the positioning of the tools with reference to the die-block. Each tool is arranged to reciprocate upon a carrier having a portion directly co-operating with the die-block and movable toward and from said die-block and angularly with respect thereto. The carrier may thus adapt itself to readily enter the die-block-groove which is to direct it into the operating position. As herein disclosed, the carrier is in two portions, a slideable primary portion 10 and a secondary portion pivoted upon said primary portion. Upon the secondary portion the awl- and driver-holder is mounted, the movement of this holder alining either of the tools with the corresponding die-block-passage. To 15 cause the movement of the carriers with respect to the die-block, I preferably furnish means for shifting all the carriers simultaneously, as by a movable cam-plate, and there is also preferably associated with the carriers a guide which retains the secondary portions in a definite angular relation after they have left the die-block-grooves, so they will be correctly located to re-enter said grooves. The die-block, as herein 20 illustrated, is furnished with means, as a spring, for holding it above its operating position. In this relation, the tool-carrier may enter the die-block-grooves and be alined with the terminal recesses. Then, upon lowering the block, the recesses receive and retain the operating sections 25 selected by the particular block, while locking means holds the block for the fastening-inserting operation. In its broader aspect, the selective positioning of operating sections under the control of interchangeable die-blocks is not a part 30 of my invention, it being disclosed and claimed in the application for Letters Patent of the United States, filed on October 15, 1931, in the name of Fred L. MacKenzie and bearing the Serial No. 568,969.

45 An additional feature of the invention has to do with a novel arrangement for supplying the fastenings for insertion by the mechanism or mechanisms previously referred to. When there is a plurality of sections for inserting fastenings, a fastening-supplying means is carried by each section, this fastening-supplying means, in the present instance, being made up of feeding and cutting and transferring mechanisms. When the section includes a carrier and an awl- and driver-holder movable thereon to bring either of these tools into operating position, I preferably provide connections to the holder-moving means for actuating the cutting and transferring mechanism. Thus, a fastening, ready for insertion, 50 may be fed conveniently to the inserting mechanism regardless of the positions of the sections. There is herein shown as combined with plural awls and their actuating means, fastening-feeding means individual to each awl, together with means whereby the feeding means is caused to advance the material to an extent dependent upon the penetration of the work by the corresponding awl. Each inserting means is thereby supplied with a fastening of the length best suited to the conditions it encounters in the heel-seat, regardless of the associated inserting means. This independence is best obtained through yieldable operating connections, which connections 55 may include a fluid. With each awl is associated what is herein disclosed as a reciprocatory actu-

ating member, and I may cause this actuating member to move into engagement with operating connections for the fastening-supplying means, this resulting in their action in accordance with the length of travel of the awl and the thickness 80 of the material pricked by said awl. When each complete fastening-inserting means includes both an awl and a driver, and, as the actuating member is common to both, there is included means for causing said actuating member to effect the operating connections for the fastening-supplying means only upon the operation of one of the tools, as the awl. This is accomplished by connections to means for moving tools into operating relation to their actuating member, said connections rendering the operating connections 85 for other tools ineffective.

Other features of the invention will become obvious upon consideration of the following description and the appended claims. In the accompanying drawings,

Fig. 1 is a top plan view of a particular embodiment of my invention;

Fig. 2 is a broken front elevation thereof;

Fig. 3, a horizontal section on the line III—III 100 of Fig. 2, with the operating sections removed;

Fig. 4 shows in elevation, looking from the left in the preceding figures, the cam and a portion of the connections for applying final pressure to the work;

Fig. 5 is an enlarged sectional elevation of one of the pricking and fastening-inserting mechanisms and its more closely associated elements;

Fig. 6, a broken side elevation of a back-stop for the work;

Fig. 7, an enlarged vertical section on the line VII—VII of Fig. 3; and

Fig. 8, a broken side elevation, particularly showing the main actuating shaft.

From a main frame or base 10 rise spaced rods 115 12, 12 carrying at their upper extremities a cross-bar 14. Movable vertically in the cross-bar is a plunger 16 having pivoted upon its lower extremity for movement into and out of operating position a work-support or jack-post 18, shown in Fig. 2 120 of the drawings as arranged to receive a lasted shoe S. As is customary in apparatus of this character, pressure is applied to the work in preparation for the inserting operation, this being made up of a preliminary or measuring pressure 125 and a final or clamping pressure. In the present instance, this effect is obtained by movement of the jack-post by such means as is indicated at M in Fig. 2 and fully disclosed in Letters Patent 130 of the United States No. 1,847,274, Standish, March 1, 1932. Since this pressure mechanism is not directly concerned with the present invention, it will not be described, beyond the statement that it employs a fluid connecting medium, as oil, contained within the plunger 16, which is hollow, and that preliminary pressure is applied through connections 20 joined to a starting treadle 22 fulcrumed at the bottom of the frame 10, while final pressure is transmitted through connections 24 from a cam 26 carried by a main actuating shaft 140 28 journaled horizontally near the lower portion of the frame.

Supported upon the frame below the jack-post 145 18 is a bracket 30 (Figs. 2, 5 and 6) containing a vertical bore 32 furnishing a socket to receive a spindle 34 depending from the under side of some one of a set of die-blocks 36, there being in the set a block for each fastening-design which is to be employed. The angular relation of each die-block, with respect to rotation about the axis of 150

its spindle, is fixed in the operating position by a pin 37 which enters an opening in the top of the bracket 30 adjacent to the bore 32. Near the periphery of the block is a series of upwardly and inwardly inclined passages 38, corresponding to the location of the fastenings of the particular design to which said block corresponds. The lower portion of each passage has a frusto-conical enlargement or recess 40 (Fig. 5), from which 5 opens outwardly through the edge of the block a groove 42, which nowhere emerges through the upper block-surface with which the work contacts. Between the spindle 34 of each block and the bottom of the socket 32 is a compression-spring 44 of such dimensions that the die-block, the spindle of which is inserted in the socket and not finally secured in place, is elevated somewhat above the top of the bracket 30. In the normal or operating position, the spring is compressed, 10 so the under side of the block rests upon the bracket, being secured in this position by a rotatable latch 46. The reasons for thus forming and supporting the die-block will later be made clear. When the jack-post 18 is swung in from the forwardly inclined work-receiving position to its vertical operating position, the heel-seat of the advanced shoe is alined with the die-block, ready 15 for the insertion of the seat-securing fastenings after pressure has been applied by the mechanism M. The central work-engaging portion of the die-block, as best seen in Fig. 5, is preferably provided with a concavity so formed that, under the applied pressure, the heel-seat, which is in temper, will be molded to substantially fit the concave end of the heel to be attached. To correctly 20 locate the jacked work for co-operation with the particular nailing design contained in the die-block employed, this design varying with the size and style of shoe being operated upon, a back-stop may be provided. This, as appears in Figs. 1 and 6, consists of a fork 48 arranged for engagement with the counter-portion of the jacked shoe. The fork depends from a slide or carrier 50 movable horizontally upon a bar 52 extending 25 toward the jack-post from a bracket 54 rising from the frame. Secured horizontally at one side of the slide is a tubular spindle 53, upon which a vertical sector 56 is clamped for angular adjustment about the spindle by a split hub 55. Upon 30 the periphery of the sector appears a series of graduations 57 (Fig. 1), with which is associated an index-plate 59 secured upon the slide 50. Within the spindle is rotatable a short horizontal shaft 58. The shaft has at one extremity a crank-handle 60 carrying a spring actuated latch 62, which may be caused to engage any one of a series of openings or retaining devices 64 about the sector (Fig. 6). Also fast upon the shaft 58 is a pinion 66 meshing with a rack 68 formed upon 35 the upper face of the bar 52. When the operator has selected the die-block 36 to be utilized for the particular work into which the fastenings are to be driven, he moves the crank 60 to a point at which it is secured by its latch 62 in the opening 40 64 corresponding to the size of the shoe. This brings the fork 48 into the correct position to so locate the jacked shoe over the die-block that the openings in said die-block will be symmetrically related to the periphery of the insole. This setting, however, may be modified by adjustment of the sector 56 about the spindle 53, this giving a further adjustment taking into account the peculiar form or style of the work. As the crank, 45 sector and all the associated stop-adjusting elements are movable with the slide 50, they may 50 readily be moved rearwardly by rotating the crank, thus leaving ample space for changing the die-blocks.

For each different inserting position for the fastenings to be driven into the heel-seats of the entire range of sizes of shoes to be operated upon, a heel-seat-pricking, fastening-measuring and feeding and fastening-inserting section A (Fig. 5) is movably mounted upon the frame 10. These operating sections may be identical in their arrangement and but one will be described in detail. As illustrated, each section has a primary carrier 70 provided with arms 72, 72 movable in horizontal ways in the frame. Arranged to turn about a vertical pivot-rod 74 at the inner extremities of the arms is a secondary carrier 76, which has spaced side-plates 78, 78. Mounted upon the tops of these side-plates is a mechanism B for supplying the fastenings to be inserted. The lower portion of the frame of this mechanism B has an extension 80, from which rises a frusto-conical projection 82 formed to fit within the recessed portion 40 of the die-block-passage 38, and having a passage 84 to register with said passage 38 of the die-block. These openings 84 and 38 furnish a throat through which the pricking and fastening-driving operations occur. The fastening-material P may consist of wire or cord, the latter being of such a fibrous substance as paper, carried upon a reel 86 for each operating section 105 A, the reels being shown (Fig. 1) as arranged in two groups above and outside the sections. The flanges of each group of reels may rest upon spaced rolls 88, 88 rotatable in end-plates 90 secured to the frame. At the axis of each reel is 110 an opening through which passes a loosely fitting rod 92 supported by the end-plates and retaining the reels against accidental displacement. The rod is readily separable from the end-plates to facilitate the replacement of empty reels. From 115 each reel the fastening-material is led between a lower feed-roll 94, journaled in the frame of the corresponding mechanism B, and an upper pressure-roll 96 rotatable upon a pivoted arm 98 and urged toward the companion roll by a spring 100. 120 The roll 94 is rotated to advance the fastening-material by a lever 102, upon which is formed a segment 104 meshing with an idle pinion 106, which pinion, in turn, engages a segment 108 arranged to turn adjacent to the roll 94 and having 125 a one-way connection 109 thereto. A spring 110 draws the lever 102 into contact with an actuating rod 112 movable through the pivot-rod 74, which is tubular. The oscillation of the lever 102, as a result of the elevation of the rod 112 by the work-pricking mechanism, as will shortly be described, turns the feed-roll 94 to advance the fastening-material to a definite extent dependent upon the thickness of the heel-seat-stock. The fastening-material thus fed passes down a passage 114 and through a passage 116 in a sliding cutting and transferring member 118 mounted to reciprocate in horizontal ways near the bottom of the mechanism B. In its movement, the slide 118 carries its passage 116 from alinement with the passage 114 into registration with the throat 84, 38. After the fastening-material has been fed into the passage 116, the slide is reciprocated and the fastening cut to the proper length, dropping upon a yieldable retaining member 124, which temporarily 130 holds the fastening in the passage 116. The manner of actuation of the slide will be developed in connection with the description of the pricking and driving mechanism.

Fulcrumed between the side-plates 78 of each 150

operating section A is an upper bell-crank-lever 126 and a lower bell-crank-lever 128. Engaging the upper lever by a hook 130 and the lower lever by a depression 132, and carried by these levers to be moved outwardly and inwardly between the plates 78 by what approximates a parallel motion, is a holder 134 containing two passages inclined at substantially the angle of the passages 38, 84 and 116. This inclination is such that the 10 openings are pricked in the heel-seat and the fastenings driven through said openings substantially normal to the curvature of the last-plate, though this inclination may be somewhat increased to insure clinching of the fastenings inwardly. In the inner passage of the holder, an awl 136 is arranged to reciprocate, while the outer passage contains a reciprocatory fastening-driver 138. The shank of each of these members terminates in a ball 140. Normally, or at the beginning of an operating cycle, the ball of the awl 136 rests within a cylindrical recess 141 in the upper extremity of an actuating bar 142 arranged to reciprocate in a guide member 144 secured between the side-plates 78. An end-portion 146 of 20 the bar overhanging the ball holds the latter against longitudinal displacement. At the same time, the ball of the driver 138 is locked against movement, and held in alinement with the bar-recess 141 ready to enter it, by resting within a recess 148 in the guide 144. When the ball of 30 the driver is engaged by the bar 142, the awl is locked by a recess 150 in the guide at the opposite side of the bar.

As illustrated in Fig. 5, the holder 134 is positioned with the awl 136 alined with the throat 84, 38 ready for the pricking of the work held against the die-block 36. Simultaneously, the fastening-material P of each section A in use is fed from its reel 86 ready for cutting. At the lower extremity 40 of each actuating bar 142 is formed a cylinder 152, in which operates a piston 154 pivotally connected to a floating lever 155, one end of which may be shifted along a horizontal passage 156 in the frame as the carrier 70 is moved in changing the die-blocks 36. This latter operation will be 45 hereinafter more fully described. The other end of the lever is received between horizontal cheeks 158 at the top of a vertically reciprocatory plunger 160 guided within a bracket 162 secured to the frame. At the bottom of the plunger is a roll 164 (Figs. 2 and 3) entering a cam-groove in a disk 166 fast on the shaft 28. Power may be applied to this shaft through a pulley 170 and a single-rotation clutch 172 (Fig. 7) governed by the 50 treadle 22 upon its full depression. As already indicated, when the sections are drawn out for changing the die-block, each lever 155 will be moved outwardly, its end traveling in the passage 156. At this time, it will leave its position between the cheeks 158, and for its support I have 55 provided a curved rail 174 carried by the frame and which guides the end of the lever back between the cheeks upon restoration of the parts to their operating positions. The piston 154 has an axial passage 176 joined by a flexible tube or conduit 178 to a horizontal curved pipe 180, this being piped at 182 (Figs. 3 and 7) through a valve-casing 184 into a by-pass 186 opening into the opposite extremities of a cylinder 188 belonging to a pump D and supported on the frame. The piston 190 of this pump is continuously reciprocated by driving connections 192 to the shaft 28 to create a pressure upon the oil or other transmitting fluid in the system, this being sufficient 65 to force the awls through heel-seat material of

maximum resistance to the plate of the last within the shoe. In the by-pass 186 is a relief-valve 194 extending into a casing 196 and held upon its seat by a spring 198. The pump-pressure is delivered through a check-valve 200, the lower portion of the by-pass, a passage 202 in a valve-plunger 204 movable in the casing 184 and held normally open by a spring 206, the piping 184 and the curved pipe 180, where it divides and passes through the flexible tubes 178 to act simultaneously in all the cylinders 152, thus holding said cylinders against downward movement while the cam 166 is acting to force up the levers 155. The awls of the holders 134 which are locked in operating position by the die-block 36 are thereby caused to penetrate the heel-seat of the jacked shoe through the throat 84, 38. When the awls strike the last-plate, the resistance causes the valve 194 to yield under the influence of the pump-pressure, opening the by-pass. The pressure is consequently relieved by circulation through the by-pass, and any further movement of the levers 155 merely raises the pistons 154 idly in their cylinders. The amount of pressure exerted by the awls may be varied simultaneously 100 for the set which is in use by adjustment of an abutment-screw 208 for the spring 198. This causes the spring to offer such a resistance that the valve will not open the by-pass until ample force has been exerted to drive the awls through 105 the work, yet without enough pressure to mutilate the last-plate.

It will be obvious that the distance which an awl travels after emerging from its die-block-passage until it strikes the last-plate will be 110 equal to the thickness of the heel-seat-material pricked, and that movement of the actuating bar 142 and its cylinder 152 will be stopped at substantially the same time as the awl. This relation is utilized to determine the correct length of 115 the fastening-material P which is to be cut for driving into the pricked opening. The lower extremity of the actuating rod 112 for each fastening-supplying mechanism B has a shoulder 210, which, at the time of pricking, lies above the 120 inner portion of a fork at the end of an arm 212 pivoted upon a three-armed lever 214 fulcrumed at 216 upon a depending portion 218 of each section A. The arm 212 is limited in its downward movement upon its pivot by a boss projecting from 125 the lever 214 and upon which it rests. On the exterior of the corresponding cylinder 152, below inner rounded ends of the arm 212, is a projection 220. The distance between the projection 130 an arm is such that, after the awl has reached the heel-seat-material, they will travel in contact, the arm being moved by the projection a distance proportionate to the thickness of the heel-seat-material. The resulting movement of the rod 112 by the arm is transmitted through the 135 lever 102 and gearing 104, 106, 108, which is so designed that the material P is fed forward by the roll 94 an amount somewhat greater than the thickness of the heel-seat-material, to allow it to be properly upset or clinched. Since the upward travel of the projection 220 varies with the thickness of the work, it is thus automatically measured, and the fastening-material fed in accordance with such measurement.

At the termination of the pricking stroke of 145 the awls, the cam 166 causes them to be withdrawn with the actuating bar 142 to the initial positions. The retraction of each bar when its lever 155 is moved down may be made certain by contact of shoulders at 221 (Fig. 5) upon the cyl- 150

inder 152 and piston 154. This again alines the ball-receiving recess 141 with the locking recesses 148 and 150 of the member 144. Now a driver 138 is to be brought into operating position in place 5 of each awl 136.

The material P having been fed, the corresponding slide 118 reciprocates to sever and then deliver a fastening for insertion in the pricked opening. The plunger 160 contains a vertical 10 recess, in which is guided a second plunger 222 carrying a roll 224 (Fig. 2). This roll lies within a cam-groove in a disk 226 secured to the shaft 28 and acting to reciprocate the plunger 222 in the desired time-relation. Between horizontal 15 cheeks 228 secured to the upper extremity of the plunger 222 projects, for each operating section A, the end of a lever 230 fulcrumed upon a depending portion of the guide member 144. A link 232 joins the lever 230 to the bell-crank-lever 20 128, the latter lever being, in turn, connected by a link 234 to the bell-crank-lever 126. Movement of the lever 230 by the cam 226 at the completion of the pricking operation, through the 25 links rocks the bell-crank-levers in a clockwise direction (Fig. 5), carrying the holder 134 to the right to shift the awl out of alinement with the throat 84, 38 and bringing the driver 138 into operating position. The ball-end 140 of the awl is now locked against longitudinal movement in the 30 recess 150, while that of the driver occupies the actuating bar-recess 141. At the beginning of the movement of lever 126, a cam-surface 236 upon it engages the lower extremity of a lever 238 fulcrumed between the side-plates 78. The upper 35 end of the lever 238 has threaded horizontally through it a contact-screw 240 engaging the slide 118 to move it across the end of the passage 114. The slide-opening 116 is thus carried quickly and with considerable force out of registration with the 40 passage 114, severing a fastening from the material P, which has been advanced through a measured distance, as already described. At first, the end of an arm 242 of lever 126 moves idly in a space 244 in the slide 118, but after the fastening 45 has been cut and has fallen upon the retaining member 124, this arm contacts with the wall at the inner side of the space and moves the slide until its passage 116 is in registration with the throat 84, 38 and with the driver 138. Through 50 a connecting link 248, the lever 230 also swings the lever 214 to carry the fastening-advancing arm 212 out of active co-operation with the rod 112, so there shall be no feed of the fastening-material during the driving movement of the 55 actuating bar 142.

With the elements positioned as above indicated, the piston 154 and the cylinder 152 of each active section A are connected unyieldingly for the operation of the driver 138. This may be 60 effected in two ways. Fixed to the shaft 28 is a cam 250, with which contacts one arm of a bell-crank-lever 252 fulcrumed upon the frame (Fig. 7). The other arm of the lever is joined to the stem 254 of the normally open valve 204. In 65 preparation for the fastening-driving, the cam moves the lever to close the valve against the force of the spring 206. The pump-pressure is thus cut off from the piping 182. The valve 194 opens and the fluid circulates idly through the by-pass. On 70 account of the substantially non-compressible character of the oil or other fluid, the cylinder and piston will act as a rigid unit, the resistance encountered by the driver 138 being insufficient to move them relatively, and the cam 166 causes 75 the lever 155 to reciprocate the driver. This,

entering the passage 116, displaces the retaining member 124 and forces the fastening which was held by the member through the now alined passages 116, 82 and 38 into the opening pricked by the awl 136. If it is desired to join the piston 154 80 to the cylinder 152 positively, rather than by the locked body of fluid, there may be formed upon the cylinder a shoulder 256 into engagement with which may be carried a shoulder 258 upon a lever 250 fulcrumed upon the mounting of the piston. The lever 260 has a roll 262 running in a slot 263 in an actuating member 264 hung upon a depending arm of the lever 214 and upon a link 266 pivoted upon another arm. When the link 248 turns the lever 214 anti-clockwise (Fig. 5) to 85 prevent fastening-feeding action by the arm 212 during fastening-driving, it also carries the actuating member 264 to the right and the lever-shoulder 258 beneath the cylinder-shoulder 256. Therefore, the piston 154 is directly coupled 90 through the lever 260 to the cylinder 152, without regard to the contained fluid, the travel of the roll 262 along the slot 263 permitting the continuing engagement of the shoulders during the driving stroke. When the coupling-lever 260 is not 95 employed, it, with the member 264, may be removed from the machine. When it is in use, the fluid connecting means may act to cushion the initial contact between the shoulders 256 and 258.

To allow the die-blocks 36 to be changed conveniently, so the fastenings may be inserted in accordance with one or another of the varying designs, the apparatus has means for moving all the inserting sections A simultaneously. Each primary carrier 70 has formed upon its arms 72, 105 72 racks 270 meshing with pinions 272 upon a vertical shaft 274 journaled in the frame. A torsion-spring 276 surrounds the shaft and is secured thereto and to the frame, acting to so rotate the shaft as to carry the section A toward the 110 die-block. Adjustably secured to each carrier 70 is a roll 278 (Fig. 1), which may be engaged by one of a series of cam-projections 280 from a generally segmental plate 282 guided to slide on the frame. Near one extremity of the plate 115 120 is formed a rack 284, with which meshes a pinion 286 fast upon a vertical shaft 288 turning in the frame and which has at its upper end a handcrank 290. Rotation of the crank anti-clockwise shifts the plate 282 to urge the cam-inclines of the projections 280 against the rolls 125 278, and thereby force all the carriers of the sections out to remove the projections 82 from beneath the die-block and temporarily hold them for the die-changing operation. To retain the 130 secondary carriers 76 at such angles about their pivots 74 that they will enter the grooves 42 in the die-block to which they correspond upon release by the plate 282, outward projections 292 from the side-plates 78 are received by depressions 294 in a generally segmental plate 296 secured to the top of the frame. Each depression 135 at its inner open end has oppositely curved and outwardly converging walls 298, 298, which engage the projections 292 and guide these into contact with substantially parallel walls 300, 300, into which the walls 298 merge. The walls 300 are so spaced from each other that each section is admitted between them without much clearance and is thus held in the correct relation for 140 again co-operating with the die-block-groove to which it belongs. After a section is freed from its depression 294 and its projection 82 is entering the alined die-block-groove 42, its pivotal connection at 74 permits it to swing, so the dif- 145 150

ferences in angular relation between the ways in which move the carrier-arms 72 and the grooves 42 will be compensated for. The changing of the die-block is accomplished as follows: With the sections A withdrawn, the spindle 34 of the desired block is inserted in its socket 32 and left supported by its spring 44 above the operating position. The crank 290 is then rotated to free the sections from the cam-projections and permit the springs 276 to move said sections inwardly. When the die-block is thus raised by its spring, the projections 82 of the sections which are to be used are free to enter the grooves 42 and locate themselves below the die-block-recesses 40. The sections which are to be inactive are held out by contact of the projections 82 with the solid or ungrooved portion of the die-block. Now the block is pressed down against the elevating force of the spring 44 and secured by the latch 46. This seats all the projections of the active sections in the block-recesses, locking them in their operating positions. The edge of the descending block moves over the other sections, which remain locked out in their inactive positions. When a change is to be again made, the die-block in use is lifted from the securing projections 82, releasing those sections which have been in use. The crank 290 is turned to retract the sections, and the substitution of the blocks made as before.

To briefly outline the general operation of the machine, all the operating sections A being forced by the cam-plate 282 away from the die-block-receiving position upon the bracket 30, a block 36, having its passages 38 and grooves 42 corresponding to the fastening-inserting design which is appropriate for the size and style of shoe being operated upon, is placed upon the bracket, being left temporarily supported by the spring 44. Then the plate 282 is moved by the crank 290 to release all the sections. The projections 82 of those sections which are to be active in the insertion of the fastenings will thereupon enter the block-grooves 42 under the influence of the springs 276, which, by their action upon the primary carriers 70 of the sections, move all of said sections inwardly until the selected projections 82 register with the block-recesses 40. The correct entrance of the projections 82 into the block-grooves was assured by the positioning of the pivoted secondary sections 76 under the influence of the depressions in the plate 296 when the sections were drawn back by the plate 282. The sections A which are not to be used are maintained inactive by the engagement of their projections 82 with the solid periphery of the block. This relation having been attained, the operator presses down the block against the spring 44 and secures it by the latch 46, thus locking the chosen sections in operating position by the seating of the projections 82 in the recesses 40. The back-stop 48, which was withdrawn during the change of the die-blocks, is adjusted under the control of the crank 60 and the divided hub 55, so the size and style of shoe being operated upon will be correctly located by the back-stop over the die-block. A shoe, the heel-seat of which is to be secured, is placed upon the jack-post 18 while this is swung forward, and then the post is brought to a vertical position above the die-block. The operator may now depress the treadle 22, lowering the jacked shoe into contact with the die-block. The work being located by the back-stop 48, continued movement of the treadle

trips the clutch 172, and the automatic operation of the machine begins. The mechanism M lowers the jack-post and applies final pressure to the work, the heel-seat-surface of the outsole being molded to the desired form by its pressure against the concave surface of the die-block, in which there are no openings, other than those of the fastening-passages 38, to deform the heel-seat. The plunger 222 initially maintains the levers 230 of all the sections A with the awls 136 registering with the projection-passages 84 and the die-block-passages 38 and said awls in alignment with the actuating bars 142 held by the recesses 141, while the drivers are maintained against movement in the guide-recesses 148. The plunger 160 is raised by the cam-disk 166 and, through the levers 155, forces the awls through the throat 84, 38 and through the heel-seat-material of the jacked shoe. The ends of the awls arriving at the last-plate, the co-operating cylinder 152 and piston 154 in the actuating connections for each previously rigid bar 142 yield, since the resistance to advance of the awls is now greater than the force exerted by the spring 198 to keep the valve 194 seated, so the by-pass 186 is opened. When the valve 194 leaves its seat upon the stopping of the awls by the last-plate, the force of the pump is absorbed by the by-pass, and the awls are relieved of undue pressure before the last-plate will have been indented by their action. As each actuating bar 142 rises in the pricking stroke, the projection 220 upon it strikes the arm 212 and, through the rod 112 and connections actuated thereby, draws from the corresponding reel 86 a length of fastening-material P proportionate to the travel of the awl in the work, and feeds this into the passage 116 in the slide 118. After this pricking stroke of the awl, they are withdrawn by the descent of the plunger 160, and the plunger 222, which up to this time has been stationary, is lowered by the cam-disk 226. Through the connections to the levers 230, all the holders 134 are shifted to carry the awls to their idle positions, locked by the recesses 150, and to bring the drivers 138 into operating relation in alignment with the throat 84, 38 and the bars 142. At the same time, connections which are actuated simultaneously with those for moving each holder 134 reciprocate the cutter-slide 118 to sever the measured fastening, and then advance said slide to align with the fastening-inserting throat its passage containing this cut fastening supported upon the retainer 124. While the fastening is thus held, the plunger 160 is again caused by its cam-disk 166 to elevate the actuating bars 142 and compel the drivers 138 to insert the fastenings in the previously pricked openings. In preparation for this and to render the driving force positive, the actuating connections are made non-yieldable, as by closing the valves 204 to cut off connection to the spring-seated valve 194, or by coupling two relatively movable portions of each actuating bar 142 by the lever 260, or both, according to the choice of the operator. The valve 204 is closed by the cam 250, and the coupling-lever brought into play by connections to the corresponding lever 230. This connection to the lever 230 is also utilized to render ineffective the movement of the arm 212, which previously fed the fastening-material from each reel 84, the fastenings being supplied only upon the pricking stroke.

Having described my invention, what I claim

- as new and desire to secure by Letters Patent of the United States is:
1. In a machine for operating upon shoe-bottoms, a plurality of movable tools, a movable operating member, and connections from the operating member to each tool and including a pressure-transmitting medium common to plural tools, said connections being arranged to yield independently of one another upon encountering by the tools of a predetermined resistance. 80
  2. In a machine for operating upon shoe-bottoms, a plurality of movable tools, a movable operating member, and connections from the operating member to each tool, said connections being arranged to contain a fluid and to yield against the resistance of said fluid. 90
  3. In a machine for operating upon shoe-bottoms, a plurality of movable tools, a movable operating member, connections from the operating member to each tool, said connections being arranged to yield independently of one another upon encountering by the tools of a predetermined resistance, and means common to the connections of plural tools for varying the yieldability of said connections. 100
  4. In a machine for operating upon shoe-bottoms, a plurality of movable tools, a movable operating member, connections from the operating member to each tool, said connections being arranged to contain a fluid and to yield against the resistance of said fluid, and a source of fluid-pressure common to the connections of plural tools. 105
  5. In a machine for operating upon shoe-bottoms, a plurality of movable tools, a movable operating member, connections from the operating member to each tool, said connections being arranged to contain a fluid and to yield against the resistance of said fluid, a source of fluid-pressure common to the connections of plural tools, and means arranged to vary the fluid-pressure applied from the source to the plural connections. 110
  6. In a machine for operating upon shoe-bottoms, a reciprocatory tool, a movable operating member therefor, connections between the operating member and tool and including a co-operating cylinder and piston, a source of fluid-pressure, and connections for the fluid between the source and cylinder. 115
  7. In a machine for operating upon shoe-bottoms, a reciprocatory tool, a movable operating member therefor, connections between the operating member and tool and including a co-operating cylinder and piston, a source of fluid-pressure, connections for the fluid between the source and cylinder, and means arranged to vary the pressure applied from the source to the connections. 120
  8. In a machine for operating upon shoe-bottoms, a reciprocatory tool, a member movable to cause the operation of said tool, a co-operating cylinder and piston, the movement of the operating member being transmitted to one of these elements and the other element being connected to the tool, a pump, and fluid-connections between the pump and cylinder. 125
  9. In a machine for operating upon shoe-bottoms, a reciprocatory tool, an operating member for said tool, a co-operating cylinder and piston connecting the tool and member, a pump provided with a piston, a by-pass about the pump-piston, a valve yieldable in the by-pass, and fluid-connections between the pump and cylinder. 130
  10. In a machine for operating upon shoe-bottoms, a reciprocatory tool, an operating member for said tool, a co-operating cylinder and piston connecting the tool and member, a pump provided with a piston, a by-pass about the pump-piston, a valve yieldable in the by-pass, means arranged to vary the resistance of the valve to opening, and fluid-connections between the pump and cylinder. 135
  11. In a machine for operating upon shoe-bottoms, an awl, a reciprocatory actuating bar to which the awl is connected and having at its extremity opposite the awl a cylinder, a piston movable in the cylinder and provided with a passage, a lever to which the piston is joined, a reciprocatory operating plunger engaging the lever, a fluid-pump, and connections from the pump to the piston-passage. 140
  12. In a machine for operating upon shoe-bottoms, an awl, a reciprocatory actuating bar to which the awl is connected and having at its extremity opposite the awl a cylinder, a piston movable in the cylinder and provided with a passage, a lever to which the piston is joined, a reciprocatory operating plunger engaging the lever, a fluid-pump having a cylinder and a reciprocatory piston, a by-pass opening into the pump-cylinder at opposite sides of the piston, a valve in the by-pass, a spring normally holding the valve closed, and connections from the pump to the piston-passage. 145
  13. In a machine for operating upon shoe-bottoms, a plurality of awls, a reciprocatory actuating bar to which each awl is connected and having at its extremity opposite the awl a cylinder, a piston movable in each cylinder and provided with a passage, a lever to which each piston is joined, a reciprocatory operating plunger engaging the levers, a fluid-pump having a cylinder and a reciprocatory piston, a by-pass opening into the pump-cylinder at opposite sides of the piston, a valve in the by-pass, a spring arranged to close the valve, an adjustable abutment for the spring, and connections from the pump to the piston-passage. 150
  14. In a machine for operating upon shoe-bottoms, a plurality of reciprocatory awls, actuating connections for each awl including a co-operating cylinder and piston, a pump, and fluid-connections joining each cylinder to the pump. 155
  15. In a machine for operating upon shoe-bottoms, a plurality of reciprocatory awls, actuating connections for each awl including a co-operating cylinder and piston, a pump, a pipe leading from the pump, and a flexible conduit connecting each cylinder with the pipe. 160
  16. In a machine for operating upon shoe-bottoms, a plurality of reciprocatory awls, actuating connections for each awl including a co-operating cylinder and piston, a pump, fluid-connections joining each cylinder to the pump, and a valve simultaneously controlling the pump-pressure applied to the connections for all the cylinders. 165
  17. In a machine for operating upon shoe-bottoms, a plurality of reciprocatory awls, actuating connections for each awl including a co-operating cylinder and piston, a pump, a pipe leading from the pump, a conduit connecting each cylinder with the pipe, and a yieldable valve operating in the pipe. 170
  18. In a machine for operating upon shoe-bottoms, plural reciprocatory tools, actuating connections common to plural tools, said connections having portions arranged to yield relatively during the operation of one tool, and means for 175

- locking the portions against yield during the operation of another tool.
19. In a machine for operating upon shoe-bottoms, plural reciprocatory tools, actuating connections common to plural tools, said connections having portions arranged to contain a fluid and to yield relatively against the resistance of said fluid during the operation of one tool, and means for locking the fluid in the connections to resist the yield of the portions during the operation of another tool.
20. In a machine for operating upon shoe-bottoms, plural reciprocatory tools, actuating connections common to plural tools, said connections having portions arranged to yield relatively during the operation of one tool, and a member movable upon one portion into engagement with the other portion and thereby locking said portions against yield during the operation of another tool.
21. In a machine for operating upon shoe-bottoms, plural reciprocatory tools, actuating connections common to plural tools, said connections having portions arranged to yield relatively during the operation of one tool, a member movable upon one portion into engagement with the other portion and thereby locking said portions against yield during the operation of another tool, means for preparing for the change in the operation of the tools, and connections to said means for moving the member.
22. In a machine for operating upon shoe-bottoms, plural reciprocatory tools, actuating connections common to plural tools, said connections having portions arranged to contain a fluid and to yield relatively against the resistance of said fluid during the operation of one tool, means for locking the fluid in the connections to resist the yield of the portions during the operation of another tool, and a locking member movable upon one of the portions into engagement with the other portion.
23. In a machine for operating upon shoe-bottoms, a reciprocatory awl, a reciprocatory driver, actuating connections for the awl and driver and including a co-operating cylinder and piston, a pump, piping connecting the pump and cylinder, and a valve arranged to open and close the connections through the piping between the pump and cylinder.
24. In a machine for operating upon shoe-bottoms, a reciprocatory awl, a reciprocatory driver, actuating connections for the awl and driver and including a co-operating cylinder and piston, a pump, piping connecting the pump and cylinder, a valve arranged to open and close the connections through the piping between the pump and cylinder, and means for operating the valve under the power of the machine.
25. In a machine for operating upon shoe-bottoms, a reciprocatory awl, a reciprocatory driver, actuating connections for the awl and driver and including a co-operating cylinder and piston, and a member movable to lock the cylinder and piston against relative movement.
26. In a machine for operating upon shoe-bottoms, a reciprocatory awl, a reciprocatory driver, actuating connections for the awl and driver and including a co-operating cylinder and piston, a member movable to lock the cylinder and piston against relative movement, a pump, piping connecting the pump and cylinder, a valve arranged to open and close the connections through the piping between the pump and cylinder, means for operating the valve under the power of the machine, means for rendering either the awl or driver operative, and connections to the last-mentioned means for moving the locking member.
27. In a machine for operating upon shoe-bottoms, a plurality of movable tools, a movable operating member, connections from the operating member to each tool and including a pressure-transmitting medium common to plural tools, said connections being arranged to yield independently of one another upon encountering by the tools of a predetermined resistance, and means for locking the said connections against yield.
28. In a machine for operating upon shoe-bottoms, a plurality of movable tools, a movable operating member, connections from the operating member to each tool, said connections being arranged to contain a fluid and to yield against the resistance of said fluid, and means for closing the connections against movement of the fluid.
29. In a machine for operating upon shoe-bottoms, a plurality of movable tools, a movable operating member, connections from the operating member to each tool, said connections being arranged to contain a fluid and to yield against the resistance of said fluid, a source of fluid-pressure common to the connections of plural tools, and means for closing communication between the connections and the source.
30. In a machine for operating upon shoe-bottoms, a reciprocatory tool, an operating member for said tool, means for moving the member under the power of the machine, a co-operating cylinder and piston connecting the tool and member, a pump, fluid-connections between the pump and cylinder, and a valve in the connections.
31. In a machine for operating upon shoe-bottoms, a reciprocatory tool, an operating member for said tool, a co-operating cylinder and piston connecting the tool and member, a pump provided with a piston, a by-pass about the pump-piston, a yieldable valve normally closing the by-pass, fluid-connections between the pump and cylinder, a valve in the connections between the by-pass and cylinder, and means for operating the last-mentioned valve under the power of the machine.
32. In a machine for operating upon shoe-bottoms, a holder, an awl and a driver mounted to reciprocate in the holder, a reciprocatory actuating member, means arranged to move the awl, driver and actuating member laterally into and out of operating position, and means for moving the holder and actuating member relatively to cause said actuating member to co-operate directly with either the awl or the driver.
33. In a machine for operating upon shoe-bottoms, a holder, operating tools comprising an awl and a driver mounted to reciprocate in the holder, a reciprocatory actuating member for the tools, and means for moving the holder to cause either of the tools to be alined with the actuating member, said holder and actuating member being free to move laterally with respect to this movement of alinement.
34. In a machine for operating upon shoe-bottoms, a holder, operating tools comprising an awl and a driver mounted to reciprocate in the holder, a reciprocatory actuating member for the tools, means for moving the holder to cause either of the tools to be alined with the actuating member, and means into engagement with which the other tool is carried to retain it against movement, said holder, actuating member and retaining means being free to move together.
35. In a machine for operating upon shoe-bottoms, a member provided with a fastening-passage, a holder, an awl and a driver mounted to

reciprocate in the holder, levers fulcrumed to turn at points separated from one another and upon which the holder is supported, and means for simultaneously oscillating the levers to aline 5 either the awl or the driver with the fastening-passage.

36. In a machine for operating upon shoe-bottoms, a member provided with a fastening-passage, a holder, an awl and a driver mounted to reciprocate in the holder, levers upon which the holder is supported and furnishing when turned about their fulcra substantially a parallel motion for said holder, a reciprocatory actuating member, and means for simultaneously oscillating 15 the levers to aline either the awl or the driver with the fastening-passage and with the actuating member.

37. In a machine for operating upon shoe-bottoms, a member provided with a fastening-passage, a carrier having spaced side-plates, a holder guided between the side-plates, an awl and a driver mounted to reciprocate in the holder, and means for moving the holder to aline either the awl or the driver with the fastening-passage, the carrier 25 and holder being free to move together laterally with respect to such movement of alinement.

38. In a machine for operating upon shoe-bottoms, a member provided with a fastening-passage, a carrier having spaced side-plates, a holder guided between the side-plates, an awl and a driver mounted to reciprocate in the holder, levers fulcrumed between the side-plates and upon which the holder is supported, and means for oscillating the levers to aline either the awl or the driver 35 with the fastening-passage.

39. In a machine for operating upon shoe-bottoms, a member provided with a plurality of fastening-passages, a holder corresponding to each passage, an awl and a driver mounted to reciprocate in each holder, and means for simultaneously moving the plural holders to aline either their awls or their drivers with the corresponding fastening-passages.

40. In a machine for operating upon shoe-bottoms, a member provided with a plurality of fastening-passages, a holder corresponding to each passage, reciprocatory operating tools comprising an awl and a driver mounted to reciprocate in each holder, means for moving the plural 45 holders to aline either their awls or their drivers with the corresponding fastening-passages, and means for simultaneously reciprocating all the thus-alined tools.

41. In a machine for operating upon shoe-bottoms, a member provided with a plurality of fastening-passages, a holder corresponding to each passage, an awl and a driver mounted to reciprocate in each holder for co-operation with a fastening-passage, and a reciprocatory operating 55 member arranged to move all the holders to effect this co-operation.

42. In a machine for operating upon shoe-bottoms, a member provided with a plurality of fastening-passages, a holder corresponding to each passage, reciprocatory operating tools comprising an awl and a driver mounted to reciprocate in each holder, a reciprocatory operating member arranged to move all the holders to aline either their awls or their drivers with the corresponding fastening-passage, and an operating member arranged to reciprocate all the thus-alined tools.

43. In a machine for operating upon shoe-bottoms, a pivoted carrier, a holder movable upon 75 the carrier, an awl and a driver mounted to re-

ciprocate in the holder, an actuating member reciprocating upon the carrier, means for moving the holder to aline either the awl or the driver with the actuating member, and means effective to reciprocate the actuating member in all positions of the carrier about its pivot. 80

44. In a machine for operating upon shoe-bottoms, a movable holder, an awl and a driver mounted to reciprocate in the holder, a reciprocatory actuating member for both the awl and the driver, a lever connected to the holder, a lever connected to the actuating member, and a plunger acting upon each lever. 85

45. In a machine for operating upon shoe-bottoms, a movable holder, an awl and a driver mounted to reciprocate in the holder, a reciprocatory actuating member for both the awl and the driver, a lever connected to the holder, a lever connected to the actuating member, an inner plunger acting upon the holder-lever, and an outer plunger acting upon the actuating-member-lever. 90

46. In a machine for operating upon shoe-bottoms, a plurality of movable holders, an awl and a driver mounted to reciprocate in each holder, 100 a reciprocatory actuating member associated with each holder, an operating plunger effective to move all the holders between positions for the actuation of the awls and drivers respectively, and an operating plunger common to all the actuating members. 105

47. In a machine for operating upon shoe-bottoms, a plurality of movable holders, an awl and a driver mounted to reciprocate in each holder, a reciprocatory actuating member associated 110 with each holder, a lever connected to each holder, a lever connected to each actuating member, a plunger provided with spaced cheeks between which all the levers of the holders extend, and a plunger provided with spaced cheeks receiving all the levers of the actuating members. 115

48. The combination with a die-block, of a reciprocatory tool, and a carrier for the tool, said carrier having a portion arranged to move bodily toward and from the die-block and a second portion directly co-operating with the die-block and arranged for angular movement on the first-mentioned portion. 120

49. The combination with a die-block having a fastening-passage and a groove extending from 125 the passage through the edge of the die-block, of a primary carrier slideable toward and from the die-block, a secondary carrier pivoted upon the primary carrier, a member supported upon the secondary carrier and adapted to enter the die-block-groove and having a passage for alinement with the die-block-passage, and a tool reciprocating upon the carrier and operating in the alined passages. 130

50. The combination with a die-block having a 135 fastening-passage and a groove extending from the passage through the edge of the die-block, of a carrier movable with respect to the die-block and having a portion adapted to enter the die-block-groove and a passage for alinement with 140 the die-block-passage, a holder movable upon the carrier, an awl and a driver mounted to reciprocate upon the holder, and means for moving the holder to aline either the awl or driver with the passage in the carrier-portion. 145

51. The combination with a die-block, of a plurality of reciprocatory tools, a carrier for each tool, said carrier having a portion directly co-operating with the die-block and being arranged to move the portion toward and from the die- 150

block and to permit its angular movement, and means for moving simultaneously the carriers for plural tools.

52. The combination with a die-block having a plurality of fastening-passages and grooves extending from the passages through the edge of the block, of primary carriers slidable toward and from the die-block, a secondary carrier pivoted upon each primary carrier, a member supported upon each secondary carrier and adapted to enter a die-block-groove and having a passage for alinement with the corresponding die-block-passage, a reciprocatory tool operating in each pair of the alined passages, and a movable cam contacting with each primary carrier.

53. The combination with a die-block having a plurality of fastening-passages and grooves extending from the passages through the edge of the block, of primary carriers slidable toward and from the die-block, a secondary carrier pivoted upon each primary carrier, a member supported upon each secondary carrier and adapted to enter a die-block-groove and having a passage for alinement with the corresponding die-block-passage, a reciprocatory tool operating in each pair of the alined passages, a plate movable adjacent to all the primary carriers and provided with cam-projections contacting with each of said carriers, and means arranged to move the plate.

54. The combination with a die-block, of a reciprocatory tool, a carrier for the tool, said carrier having a portion directly co-operating with the die-block and being arranged to move the portion toward and from the die-block and to permit angular movement of said portion, and means for causing the portion to follow a definite path during separation from the die-block.

55. The combination with a die-block having a fastening-passage and a groove extending from the passage through the edge of the die-block, of a primary carrier slidable toward and from the die-block, a secondary carrier pivoted upon the primary carrier, a member supported upon the secondary carrier and adapted to enter the die-block-groove and having a passage for alinement with the die-block-passage, a tool reciprocating upon the carrier and operating in the alined passages, and a guide in contact with which the secondary carrier moves.

56. The combination with a die-block having a plurality of fastening-passages and grooves extending from the passages through the edge of the die-block, of primary carriers slidable toward and from the die-block, a secondary carrier pivoted upon each primary carrier, a member supported upon each secondary carrier and adapted to enter a die-block-groove and having a passage for alinement with the corresponding die-block-passage, a tool reciprocating upon the carrier and operating in each pair of the alined passages, a movable cam contacting with each primary carrier, and a plate having depressions to receive the secondary carriers.

57. The combination with a die-block having a plurality of fastening-passages and a groove extending from each passage through the edge of the die-block, of a fastening-inserting section corresponding to each die-block-groove, means for causing a portion of each section to enter its groove, and means common to all sections for withdrawing them from the grooves.

58. The combination with a die-block having a plurality of fastening-passages and a groove extending from each passage through the edge of the die-block, of a fastening-inserting section

corresponding to each die-block-groove, a spring urging each section toward its groove, and a member contacting with all the sections to withdraw them from the grooves.

59. The combination with a die-block having a plurality of fastening-passages, each terminating in a recess at one side of the die-block and with a groove extending from each recess through the outer edge of the die-block, of means for temporarily holding the die-block out of its operating position, a fastening-inserting section corresponding to each die-block-groove and having a projection movable through said groove into registration with the recess in the non-operating position of the die-block, and means for locking the die-block in its operating position with the section-projections seated in the recesses.

60. The combination with a die-block having a plurality of fastening-passages, each terminating in a recess at the under side of the die-block and with a groove extending from each recess through the outer edge of the die-block, of a spring for elevating the die-block above its operating position, a fastening-inserting section corresponding to each die-block-groove and having an upward projection movable through said groove into registration with the recess in the nonoperating position of the die-block, and a latch for maintaining the die-block in its depressed operating position with the section-projections seated in the recesses.

61. In a machine for operating upon shoe-bottoms, a die-block, a plurality of movable fastening-inserting sections, each section being arranged for the insertion of a single fastening and being movable individually to adapt itself to the die-block, fastening-supplying mechanism carried by and individual to each section, and means for actuating the mechanisms to supply the fastenings.

62. In a machine for operating upon shoe-bottoms, a plurality of movable fastening-inserting sections, and fastening-material-feeding, cutting and transferring mechanisms carried by each section.

63. In a machine for operating upon shoe-bottoms, a carrier, a holder movable upon the carrier, an awl and a driver mounted to reciprocate in the holder, a member for moving the holder to bring either the awl or the driver into operating position, a fastening-cutting member movable upon the carrier, and connections to the holder-moving member for actuating the cutting member.

64. In a machine for operating upon shoe-bottoms, a carrier, a holder movable upon the carrier, an awl and a driver mounted to reciprocate in the holder, a member for moving the holder to bring either the awl or the driver into operating position, a fastening-transferring member movable upon the carrier, and connections to the holder-moving member for actuating the transferring member.

65. In a machine for operating upon shoe-bottoms, a carrier, a holder movable upon the carrier, an awl and a driver mounted to reciprocate in the holder, a member for moving the holder to bring either the awl or the driver into operating position, fastening-cutting and transferring means movable upon the carrier, and connections to the holder-moving member for first actuating the cutting and transferring means to cut a fastening and then moving the cutting and transferring means to transfer said fastening.

66. In a machine for operating upon shoe-bottoms, a carrier, a lever fulcrumed upon the carrier, a holder supported upon the lever, an awl

- and a driver mounted to reciprocate in the holder, means for oscillating the holder to bring either the awl or the driver into operating position, and two fastening-supplying members movable upon the carrier, there being means arranged to actuate first one of the supplying members and then the other. 5
67. In a machine for operating upon shoe-bottoms, a carrier, a lever fulcrumed upon the carrier, a holder supported upon the lever, an awl and a driver mounted to reciprocate in the holder, means for oscillating the holder to bring either the awl or the driver into operating position, a fastening-cutting and transferring member movable upon the carrier, and a lever movable by the holder-supporting lever and actuating the cutting and transferring member, the holder-supporting lever thereafter contacting with the cutting and transferring member to again actuate it. 10
68. In a machine for operating upon shoe-bottoms, a plurality of reciprocatory awls for pricking the work, actuating means for the awls mechanism individual to each awl for feeding fastening-material, and means for causing each mechanism to advance the material to an extent dependent upon the penetration of the work by the corresponding awl. 15
69. In a machine for operating upon shoe-bottoms, a plurality of reciprocatory awls for pricking the work, actuating means for the awls, mechanism individual to each awl for feeding fastening-material, and means movable with each awl for determining the operation of the corresponding feeding mechanism. 20
70. In a machine for operating upon shoe-bottoms, a plurality of reciprocatory awls for pricking the work, actuating means including a yieldable connection for each of the awls, mechanism individual to each awl for feeding fastening-material, and means for causing each mechanism to advance the material to an extent dependent upon the penetration of the work by the corresponding awl. 25
71. In a machine for operating upon shoe-bottoms, a plurality of reciprocatory awls for pricking the work, actuating means including a fluid-connection for each of the awls, mechanism individual to each awl for feeding fastening-material, and means movable with each awl for determining the operation of the corresponding feeding mechanism. 30
72. In a machine for operating upon shoe-bottoms, an awl, a reciprocatory actuating member therefor having a contact-surface, means for feeding a strip of fastening-material step by step, and operating connections for the fastening-feeding means including a lever, the actuating member being normally spaced from the lever and movable into contact therewith to initiate the feed of the fastening material. 35
73. In a machine for operating upon shoe-bottoms, an awl, a reciprocatory actuating member therefor having a portion engaging the awl and a portion yieldable upon the awl-engaging portion, fastening-supplying mechanism, and operating connections to the fastening-supplying mechanism, the awl-engaging portion of the actuating member acting on said connections. 40
74. In a machine for operating upon shoe-bottoms, an awl, a reciprocatory actuating member therefor having a portion engaging the awl and a portion yieldable upon the awl-engaging portion and a co-operating cylinder and piston connecting the portions, a fastening-supplying mechanism, and operating connections to the fastening- 45
- supplying mechanism, the awl-engaging portion of the actuating member being movable to contact with said connections. 50
75. In a machine for operating upon shoe-bottoms, a carrier having a pivoted portion, an awl arranged to reciprocate upon the pivoted portion of the carrier, fastening-supplying mechanism supported on said portion, and operating connections for the fastening-supplying mechanism extending through the pivot of the carrier-portion and being movable with the awl. 55
76. In a machine for operating upon shoe-bottoms, a carrier having a pivoted portion, an awl, an actuating bar therefor, fastening-supplying mechanism supported on the pivoted portion of the carrier, and an actuating rod extending through the pivot of the carrier-portion and arranged for movement by the actuating bar. 60
77. In a machine for operating upon shoe-bottoms, operating tools consisting of an awl and a driver, a reciprocatory actuating member common to both the awl and the driver, means for moving the actuating member and the awl and driver relatively to establish an operating relation between the actuating member and one of the tools, fastening-feeding mechanism, connections to the actuating member for operating said feeding mechanism, and connections to the moving means for rendering the operating connections ineffective. 65
78. In a machine for operating upon shoe-bottoms, an awl, a driver, a reciprocatory actuating member, means for moving the actuating member and the awl and driver relatively to establish alternately actuating relation between the actuating member and the awl and driver, fastening-supplying mechanism, and connections to the actuating member for operating the fastening-supplying mechanism only when said actuating member is aligned with the awl. 70
79. In a machine for operating upon shoe-bottoms, an awl, a driver, a reciprocatory actuating member, means for moving the actuating member and the awl and driver relatively to establish alternately actuating relation between the actuating member and the awl and driver, fastening-supplying mechanism, connections to the actuating member for operating the fastening-supplying mechanism, and connections to the moving means for separating the operating connections when the actuating member is aligned with the driver. 75
80. In a machine for operating upon shoe-bottoms, an awl, a driver, a reciprocatory actuating member, means for moving the awl and driver to establish alternately actuating relation between the actuating member and said awl and driver, fastening-supplying mechanism, connections to the actuating member for operating the fastening-supplying mechanism, and means for moving the connections into and out of operating relation. 80
81. In a machine for operating upon shoe-bottoms, an awl, a driver, a reciprocatory actuating member, means for moving the actuating member and the awl and driver relatively to establish alternately actuating relation between the actuating member and the awl and driver, fastening-supplying mechanism, connections to the actuating member including a lever for operating the fastening-supplying mechanism only when said actuating member is aligned with the awl, and connections to the moving means for shifting the lever. 85
82. In a machine for operating upon shoe-bottoms, an awl, a driver, a reciprocatory actuating member having independently movable portions, 90

- means for coupling the portions to move together, means for moving the actuating member and the awl and driver relatively to establish alternately actuating relation between the actuating member and the awl and driver, connections to the moving means for controlling the coupling means, fastening-supplying mechanism, and connections to the actuating member for operating the fastening-supplying mechanism only when 10 said actuating member is aligned with the awl.
83. In a machine for operating upon shoe-bottoms, an awl, a driver, a reciprocating actuating member having independently movable portions, means for coupling the portions to move together, 15 means for moving the actuating member and the awl and driver relatively to establish alternately actuating relation between the actuating member and the awl and driver, fastening-supplying mechanism, and connections to the moving means for 20 controlling the coupling means and the fastening-supplying mechanism.
84. In a machine for operating upon shoe-bottoms, an awl, a driver, a reciprocating actuating member having independently movable portions, means for coupling the portions to move together, means for moving the actuating member and the awl and driver relatively to establish alternately actuating relation between the actuating member and the awl and driver, fastening-supplying mechanism, a lever, connections to the lever for controlling both the fastening-supplying mechanism and the coupling means, and connections to the moving means for shifting the lever. 30
85. In a machine for operating upon shoe-bottoms, a plurality of fastening-inserting sections independently movable into and out of operating position, a tool movable in each sec- 35

tion, means for determining the sections which are to assume operating positions, fastening-supplying mechanism associated with each section, and means effective to actuate only the fastening-supplying mechanism of the sections which are in operating position. 80

86. In combination, a fastening-inserting mechanism including one of an interchangeable set of work-contacting elements, a jack movable from a work-receiving position into co-operation with the work-contacting element included in the inserting mechanism, a back-stop for the work at the inserting mechanism, a movable carrier for the back-stop, and a member movable upon the carrier for shifting said carrier from a position at the inserting mechanism for locating the work to a position at which the carrier and member are removed from the inserting mechanism to facilitate change of the work-contacting elements. 85

87. In combination, a fastening-inserting mechanism including one of an interchangeable set of work-contacting elements, a jack movable from a work-receiving position into co-operation with the work-contacting element included in the inserting mechanism, a back-stop for the work at the inserting mechanism, a movable carrier for the back-stop, said carrier having a series of retaining devices, and a member movable upon the carrier for shifting said carrier from a position at the inserting mechanism for locating the work to a position at which the carrier and member are removed from the inserting mechanism to facilitate change of the work-contacting elements, the member being provided with a latch for engagement with any one of the retaining devices. 90 100
